UNITED STATES PATENT OFFICE.

SAMUEL B. FIELD, OF HOLBROOK, MASSACHUSETTS, ASSIGNOR OF ONE-FOURTH TO PNEUMATIC SCALE CORPORATION, LIMITED, OF QUINCY, MASSACHUSETTS, A CORPORATION OF MAINE, AND THREE-FOURTHS TO WILLIAM H. DOBLE, OF QUINCY, MASSACHUSETTS.

BOX-PANEL AND SEALING MECHANISM THEREFOR.

1,198,336.

Specification of Letters Patent. Patented Sept. 12, 1916.

Original application filed November 20, 1914, Serial No. 873,092. Divided and this application filed July 22, 1915. Serial No. 41,419.

To all whom it may concern:

Be it known that I, SAMUEL B. FIELD, a citizen of the United States, residing at Holbrook, county of Norfolk, State of Massachusetts, have invented a certain new and useful Improvement in Box-Panels and Sealing Mechanism Therefor, of which the following is a specification, reference being had therein to the accompanying drawings.

10 The invention relates to an improvement in a safety lock and sealing device for a box cover or panel and is a division of Patent No. 1,162,466, granted November 30, 1915. It is especially intended for application to folding metallic boxes to serve as shipping cases in which the goods may be packed for shipping and which can be folded into small compass to be returned to the shipper to be again used, and is especially applicable to that class of folding boxes in which the box is made of six panels in which the front is hinged to the bottom and to the two ends and the top or cover is hinged to the back, the front having a separable connection with the top and the back having a separable connection with the bottom. It is also especially applicable to that class of such folding boxes in which the panels are each formed with an inner and outer wall plate spaced apart from each other. It is to be understood, however, that the invention is not limited to a folding box or to one in which the panels are formed with hollow walls.

35 When applied to a folding box of the character above mentioned, the object is to provide a simple form of safety lock and sealing device between the top (which may be termed a cover) and a front, and between the bottom and the rear panel, which can be easily applied when the box is to be sealed up after being filled and which can be readily removed when the box is to be unpacked and which co-operates with the inter-engaging connections between the two ends of the top and bottom panels to hold the box in rigid form when set up and sealed. The seal is destroyed when opening the box and therefore serves as a tell-tale to prevent any one tampering with the box by opening the seal and closing it again unless he has an additional one of the special forms of sealing

clips, the clips themselves being simple and cheap and it is intended to use a new one every time the box is refilled.

55 The invention will be fully understood from the following description when taken in connection with the accompanying drawings and the novel features thereof will be pointed out and clearly defined in the claims 60 at the close of the specification.

In the drawings, Figure 1 is a plan view of a box embodying the invention. Fig. 2 is a vertical section on line 3—3 of Fig. 1 on an enlarged scale, showing the sealing clip 65 slipped into place but before the sealing clip is bent down into the sealing position shown in Fig. 1. Fig. 3 is a section on the same line 3—3 of Fig. 1 after the clip has been bent down into sealing position as shown in 70 Fig. 1. Fig. 4 is a detail plan of one of the sealing clips as shown in Fig. 2 before it is attached to the box and therefore before it is bent into sealing position. Fig. 5 is a section on line 5—5 of Fig. 4.

75 Referring now to the drawings A represents the front panel, B the back and E the cover or top panel. The front A has a separable connection with the top panel E by means of the sealing clips hereinafter to be 80 described and, if the box is to be used as a folding box, preferably the back B will have a similar connection with the bottom, which is not shown because in such case the connection would be exactly similar to the connection between the two panels A and E. 85 In the form of construction shown each of the panels is made with an inner wall plate 1 and an outer wall plate 2 having a space between them which is preferably braced or 90 stiffened with corrugated plates between the walls, as for instance as shown in Patent No. 941,013 dated November 23, 1909, or in any other suitable manner. In the form of construction shown in the drawings the top E 95 is hinged to the back B in such manner as to permit the top panel to be folded over against the outer face of the back.

The front edges of the plates 1 and 2 of the top panel E stop a little short of the 100 inner face of the front panel A, and into the space between the two plates 1, 2 of the said top panel, at its front edge, there is inserted a channel piece 11 which fits snugly.

between said plates 1, 2 and is firmly secured by soldering or otherwise, and has a projecting offset loop portion of peculiar form and construction to form a vertical back rest 5 12 for the upper part of the channel piece of the front panel A and to form a horizontal portion 13 which rests upon the upper end 20 of the channel piece of the front panel A. From the front lower edge of the 10 horizontal portion 13 of the channel piece 11 the loop thereof has a backward and upward sloping portion 14 which rises somewhat higher than the upper surface of the outer plate 2 of the top panel E and then has a 15 downwardly extending shoulder portion 15, and is then bent to form a part of the shank of the channel piece 11. Preferably the space of the loop formed by the bent portions 13, 14 and 15 of the channel piece 11 is 20 filled by a core 16 of metal or other suitable stiffening material.

The inner and outer plates 1, 2 of the front panel A terminate somewhat short of the under side of the top panel, and into the 25 space between said two plates there is inserted a channel plate 17 which projects above the plates 1, 2 of said front panel and forms a part of the panel. The outer face of the upwardly extending portion of said 30 channel plate 17 above the top of the outer plate 2 of the panel A is formed with a re-entrant bend making an inwardly inclined portion 18 and terminating in an outwardly extending loop portion 19. Said loop portion 35 19 has a flat upper face 20 on which rests the flat portion 13 of the channel piece 11. A stiffener core 21 is inserted into the loop of the channel piece 17.

The fastening and sealing mechanism 40 consists of one or more clips to secure together the top of the front panel and the front edge of the top panel after the box has been filled. Preferably the clips are of such form that they can be readily attached 45 and bent into sealing position in such manner as to make them secure during the transportation, and which can be bent up again to detach them, and they are of such material that although they are sufficiently strong 50 and tough to be used once they will not stand the necessary bending required for attaching them again to the box after they have once been bent to detach them. These clips are made out of sheet metal which may be 55 flexed under the blow of a hammer but have little or no resiliency and therefore they will retain any form to which they are bent.

In the preferred form of construction the 60 clip has a body portion 22 which is adapted to lie over the front inclined face 14 of the channel piece 11 and terminates at its lower end in a hook portion 23 which is adapted to go over the outer edge of the loop portion of the channel piece 17 and hook under

the flat under face of said loop as shown in Fig. 2. The other end of the body portion of the clip is bent to form a hook portion 24 which engages over the top edge of the channel piece 11 and extends at an angle to the 70 vertical portion 15 of the said channel piece 11 so that the hook portion 24 must be bent down in order to bring it flush against the face of the said portion 15. It also has an ear 25 which extends at about a right angle 75 to the portion 24 and stands at an acute angle to the outer plate 2 of the upper panel. The clips in detached condition are of the shape shown in Fig. 2 and in this form they can be easily engaged with the two channel 80 members 11, 17 as shown in Fig. 2. Then in order to securely fasten the clip in place, the portion 24 is bent down sharply as shown in Fig. 3 to bring the inner face of the portion 24 in contact with the vertical face 15 85 of the channel piece 11 and to bring the ear 25 flat down into contact with the outer face of the panel E. This can be done by the use of a suitable tool and it does not require other fastening because the metal is of such 90 character that it retains its bent form. Preferably the ear 25 is provided with a hole 26 to serve as an engaging place for a screw driver or other suitable tool to bend up the ear 25 in order to release the clip. 95 Preferably these clips are made of relatively short length and a plurality of them are used, as shown in Fig. 1 instead of employing one long clip. It is desirable to make the clips of rather thin sheet material, and 100 in order to give them the requisite stiffness it is preferable to stamp them up so as to form ribs 27. It is also preferable to make them of a metal so treated that it will have a degree of brittleness which will allow the 105 clips to be bent into the sealing form without breaking but which will be sufficiently weakened in bending the clip to remove it so that it cannot be used a second time. One way of doing this is to make a core of relatively soft metal and case hardening the 110 surface, or by tempering it to form what is sometimes termed half hard metal. Similar clips to those above described for securing the contiguous edges of the front and top 115 together are employed for securing together the contiguous edges of the back and bottom. In order to prevent the clips from sliding off endwise after they have been bent down into operative condition, the 120 channel member 14 is formed with lugs or shoulders 41, one on either side of each clip, to limit the possible range of movement. The box when set up is perfectly rigid, as the interengaging portions formed by the 125 channel pieces serve to hold the various panels in place.

While I have described the top panel as being made of inner and outer plates, 1, 2, and a channel plate 11 with its peculiarly 130

bent form making the offset front edge portions, and have also described the front panel A as being composed of inner and outer plates together with a channel plate 5 17 having the peculiar offset form to furnish bearing surfaces for the channel plate of the panel E and engaging portions for the clip, it is obvious that if the top panel and the front panel were made either solid 10 or in any other manner by which offset edges were provided to form engaging portions for the clips, they would come within the scope of the invention.

While the sealing clip above described is 15 the preferred form of seal to be used, it is obvious that the particular form of seal may be varied. Any suitable form of seal which engages the projecting portions of the adjacent edges of said two adjacent panels, 20 and is of such a character that it is practically destroyed when the seal is opened to disengage the two panels from each other comes within the scope of this invention and it is intended that the claims shall be 25 construed to cover such variable form of seal.

What I claim is:

1. A metallic box having two adjacent panels which form two of the walls of the 30 box each formed with shouldered portions along the adjacent edges of said panels, in combination with a fastening mechanism, said fastening mechanism consisting of a metallic clip bent into locking engagement 35 with the said shouldered portions of both of said panels without penetrating the surface, said clip being of sufficient flexibility and toughness to permit bending it once to form such locking engagement and which is sufficiently frangible so that it will break in an attempt to bend it a second time for engagement after it has been bent to release it from the first engagement.

2. In combination with a box having two 45 adjacent panels each formed with a shoulder portion adapted to be engaged by a hook portion of a metal clip, mechanism for fastening together said two adjacent panels, said fastening mechanism consisting of a 50 metallic clip which is formed with two hook portions to respectively engage with said shoulder portions of the two panels to fasten the two panels together, one of said

hooks being of such form that after the clip is partially engaged it requires further bending to complete the engagement, the said clip being adapted to lock said panels together solely by surface engagement of the hook members with said shoulders without penetration.

3. In combination with a metallic box having a cover, said cover and one of the adjacent panels each being formed with shouldered portions to be engaged by a clip, a fastening clip having two bent portions, one 65 of which is adapted to engage the shouldered portion of said cover and the other of which is adapted to engage with the shouldered portion of said panel, the said bent portion which engages with the cover requiring and being adapted for still further bending to complete the locking engagement without penetration.

4. In combination with a metallic box having a cover, said cover and one of the adjacent panels each being formed with shouldered portions to be engaged by a clip, a fastening clip having two bent portions, one of which is adapted to engage the shouldered portion of said cover and the other of 80 which is adapted to engage with the shouldered portion of said panel, the said bent portion which engages with the cover requiring and being adapted for still further bending to complete the locking engagement without penetration and terminating in an extension portion which engages with the face of the cover when the said clip is bent into locking engagement.

5. A metallic clip for fastening together 90 two adjacent panels of a box, said clip being composed of sheet metal having a body portion with two of its opposite edges bent around to form hook portions, one of said hook portions having a flat extension which 95 is adapted to lie against the face of one of said panels of the box while the said hook members engage the shouldered portions of said two panels.

In testimony whereof I affix my signature, in presence of two witnesses.

SAMUEL B. FIELD.
